MEMBRANE LINED TUNNEL AND METHOD
OF CONSTRUCTING SAME

Phillip A. Kinzie, Denver, Colo., assignor to Universal Hydraulic Corporation, Denver, Colo., a corporation of Colorado

Application August 14, 1934, Serial No. 739,758

16 Claims. (Cl. 61—45)

This invention has reference to tunnels, and the method of forming the same, particularly for pressure purposes and with reference especially to penstocks and the like.

5 The usual method of constructing a penstock in a tunnel for the purpose of carrying water under heavy pressure has been, as is being used at the present time in connection with the Boulder Canyon project of the Bureau of Reclamation, the United States Department of the Interior, to build a concrete lined tunnel of larger size than the penstock which is to convey the water, and to then build, construct or fabricate within the said concrete lined tunnel a pressure pipe of steel which is of smaller size than the tunnel itself but which is of such construction that it is enabled to withstand the hydraulic pressure which, in the case of the Boulder Canyon project, is approximately 300 lbs. plus. This construction renders it necessary to use a fabricated steel penstock having, in so far as pressure carrying ability is concerned, practically no relationship to the concrete lined tunnel except that the latter forms an enclosure for the former throughout its route, and thus there is lost any benefit which might be attained through use of the concrete of the tunnel itself as a pressure restraining factor, with the result that the expense of such construction is high in that both the concrete tunnel and the steel penstock enclosed thereby do not supplement each other from the standpoint of functioning as a container for the pressure fluid stream.

35 The present invention has, as an object, the provision of a composite structure wherein both the concrete lining of the tunnel, the adjacent rock or other material through which the tunnel is excavated, and the steel penstock are interrelated in such manner that they jointly combine to form the pressure fluid carrying passage, thus rendering it possible to use a lighter steel plate and at the same time cutting down the size of the concrete lined tunnel which must first be bored through the ground and then lined so that there need be provided only the actual size required for the stream and thus saving an enormous amount of material and labor cost, as will be obvious when it is considered that on the Boulder Canyon project above referred to the size of the penstock is thirty feet while the enclosing concrete tunnel is fifty feet in some sections and thirty-seven feet at others in diameter inside its concrete 55 lining.

I am well aware that the proposal to build metal lined concrete passages is not new, and that much construction work for non-pressure carrying passages has been done along this line; however, the difficulties to be surmounted in providing such a construction for the carrying of pressure have long stood in the way of any actual construction of a pressure tube of this character.

In tunnels through rock, shale or earth, where fluid is conveyed under pressure, it might often be possible to permit the earth material through which the tunnels are excavated to carry the static load produced by the confined fluid acting normal to and upon the tunnel walls, provided it were practicable to make those walls fluid tight, and thus effectually prevent any gradual escape of fluid into the seams and crevices of the adjacent material, but the inevitable escape of such fluid would progressively build up hydrostatic pressures effective, cumulatively, over ever increasing areas until the gradual and ever mounting hydraulic force so generated would finally exceed that of the resistance capacity of the earth material and serious rupture would eventually occur.

At first thought it would appear that adequate tunnel wall sealing could be easily accomplished by lining the tunnel with waterproof concrete, or some other suitable material, which would effectually restrain the escape of the pressure fluid being transported within the tunnel and, in certain instances, this actually may be done, but these are the exception rather than the rule, the reason being that the heavier of such materials, under loads, is not as is usually pictured by the lay mind for, where iron, steel, rock and other similar material are commonly considered as being rigid and unyielding, they do as a matter of fact possess the property of elasticity to a greater or lesser degree; and, in consequence deform and flow within certain limits while under stress; accordingly every load applied is accompanied by a corresponding change in shape or condition of the material to which the load is applied, and while these changes in the dimensions of the materials affected are microscopic where but an inch or two of size is concerned, they become very appreciable when similar intensities of loadings are applied to structures of large size.

As an example of this, the 50 foot diameter diversion tunnels at Boulder Canyon project hereinbefore referred to, were originally intended to serve a dual purpose, namely, to carry

the river around the dam site during the construction period, and then by plugging their outlet ends, serve as pressure tunnels to convey the water from the reservoir to the hydraulic turbines under nearly 300 pounds per square inch pressure. The rock of the canyon walls through which these tunnels were driven is amply strong to resist such a pressure, but it was found that such procedure was impracticable because of the fact that, if the tunnels were subjected to this pressure, the elasticity of the rock would, in yielding to accommodate it, open up cracks of approximately $\frac{1}{4}$ " width extending longitudinally along the crown of the tunnel bore, and when this occurred, the concrete lining would likewise be ruptured and would permit the water under pressure to escape into the crevices of the rock and there build up pressure over constantly increasing areas, until finally the canyon walls would inevitably give way and be shattered.

To overcome this condition metal linings were examined and it was found that they would have to be made nearly four inches thick in order to withstand the service required. This was prohibitive.

Further investigations showed a fluid tight lining or membrane would have to expand and contract, or to "breathe" in response to movement with the rock and the concrete lining as varying pressure loadings were imposed, for, inasmuch as these tunnels would be serving as penstocks to the turbines in the power plant, the varying turbine loadings would be accompanied by rapid and frequent pressure variations in these tunnels and would so produce rapid and frequent changes in their circumferential dimensions, and inasmuch as thousands of such cycles would occur every day it is evident that, to prevent failure, the water tight membranes or linings would have to be so constructed as to permit of these rapid and frequent changes in size without fatiguing the metal composing them.

Many different forms of construction were examined and found wanting in one respect or another, until finally, it appeared that no reasonable solution would be found, whereupon, the placing of 30 foot diameter steel pipes inside and independent of the tunnel walls was adopted.

Subsequently the solution embodied within this application was developed, worked out, and found to be adequate.

In the following objects of this invention are found the affirmative responses to the three prime requisites to an economical and reliable solution of this problem, which are:

First.—To provide a fluid tight membrane which effectually confines the fluid within the tunnel bore without, in so doing, preventing the complete and free transmission of the hydrostatic loads produced by the confined fluid to the adjacent walls formed by the material through which the tunnel is excavated.

Second.—To provide a fluid tight membrane which freely responds to the rapid changes in the circumferential dimensions of the tunnel as varying pressure intensities cause these to change.

Third.—To provide a membrane lining, which adequately drains upon its exterior surface in such manner that, should pressure fluid escape from within to its exterior surface, that fluid will positively be carried away before it has an opportunity to gain access to the fissures and

crevices contained within the material through which the tunnel passes, and which likewise thus effectually restrains any tendency for localized pressure zones to form between the outer surface of the membrane and the encasing material in contact therewith, consequently preventing "blistering" of the membrane when the pressure on the fluid within the tunnel and its enclosing membrane is released.

Inasmuch as it is not practicable to definitely establish the location of every crack that will be formed when the tunnel is subjected to internal pressure, the expansion joints in the membrane cannot always be individually located at each crack, and in consequence of this condition, the membrane must be so arranged that it will be capable of sliding upon the enclosing and supporting material without sufficient sliding resistance or friction being developed as to dangerously stress or rupture the membrane as such movement occurs.

As concrete is one of the most favored and widely used materials employed for filling the annular space between the outer surface of the membrane and the enclosing walls of the tunnel bore, it will be assumed in this description that it is so used herein, and it will likewise be assumed that a relatively light sheet metal such as steel, or wrought iron, or the like, is employed as the material for the fluid tight membrane, it being understood, of course, that other materials than those specifically identified herein may be used without departing from the spirit of my invention.

With these objectives in view it then becomes evident that if the exterior surface of the fluid tight membrane is so treated as to permit it to slide with the least practicable resistance, and if the coefficient of such sliding resistance be established by trial, then the product of the internal fluid pressure per unit of area times this coefficient of resistance, divided into the desired working stress of the material employed for the fluid tight membrane will give the circumferential distance between the longitudinal expansion joints which must be provided therein, and with this foundation on which to erect the analytic premises a complete mathematical solution of each installation may be worked out in full detail.

To provide the most favorable conditions for the relatively small circumferential displacements between the exterior membrane surface and the encasing concrete, I preferably cover the membrane with a wrapping of heavy asbestos paper, which is ideal for this purpose as it is insoluble in water, does not oxidize or decompose, and still permits the required sliding on concrete with less resistance than any other commercially obtainable product known to me at the present time.

In encasing the fluid tight membrane with its expansion joints, asbestos paper wrappings with drainage ropes are employed as lashings retaining the asbestos paper wrappings in place, but the concrete so used usually has a fairly high water content to afford good workability, and such water infiltrates into the interstices of the drainage ropes, carrying fine cement particles with it, and thus tends to clog and seal these ropes; to compensate for this clogging tendency I impregnate these ropes with a mixture of soap and sugar, or other suitable materials of a readily soluble nature, so that any leakage readily dissolves and leaches out these materials and

thus affords easy escape to the main drains provided to carry it away.

Another object of this invention is the method of placing the membrane in position. The great size of tunnel penstocks, as now used in modern power developments, renders it essential to build such membrane liners in progressive stages from the bottoms of the tunnels towards the ceilings, employing jumbo collapsible forms, to support and carry the relatively thin linings while they are being assembled and then concreted in, after which the forms are collapsed, withdrawn and moved ahead for the next section, and it is to this method that the present invention also refers.

With the above and other objects in view there will now be described particular constructions and methods according to the present invention which are for the purpose of disclosing the same in accordance with the requirements of the patent statutes, and which have been illustrated in the accompanying drawings wherein:

Fig. 1 is a transverse end sectional view through a tunnel in accordance with the present invention;

Fig. 2 is a fragmentary end sectional view enlarged of the means providing for expansion of the metal membrane;

Fig. 3 is a view similar to Figure 2 of another means of compensating for expansion and contraction;

Fig. 4 is a view similar to Figures 2 and 3 of still another means of accommodating expansion and contraction under pressure;

Fig. 5 is a part section view, longitudinally of the conduit tunnel or penstock shown in Figure 1;

Fig. 6 is an enlarged sectional detail view transversely in the direction of the arrows 6-6 of Figure 5;

Fig. 7 is an enlarged sectional detail view in the plane of the line 7-7 of Figure 5;

Fig. 8 is a view similar to Figure 1 of a modified construction;

Fig. 9 is a perspective view of a detail of the drainage and expansion means of the construction shown in Figure 8;

Fig. 10 is an enlarged detail, in transverse section, of the drainage conduit shown at the bottom of Figure 8.

In detail, the structure of the present invention, as illustrated, may be fabricated by first boring a tunnel in the earth of a sufficient size, in cross-section, to permit of installing the water tight metal membrane with its associated expansion joints, drainage ducts, etc., and filling the space between the two with concrete to form a tunnel structure in which the natural substance of the terrain through which the tunnel is bored carries a large proportion of the hydraulic load. In the bottom of the tunnel and surrounded by concrete A is a drain channel 2, and parallel therewith, but spaced as shown, are formed, in the concrete, the channels 3, 4 and 5 for the expansion and contraction elements to be hereinafter described. Circumferentially embedded in the concrete A forming the tunnel are ropes 6 which are crossed longitudinally by ropes 7, this net-work being clearly shown in Figure 5, and the circumferential ropes are looped down into, or have their ends extending into, the drain channel 2, as shown at 6, in Figures 1, 5 and 7. These ropes

tunnel is in place, constitute drainage passages which relieve, to the channel 2, any pressure which might otherwise tend to build up between the concrete A and the metal membrane 1.

The metal membrane or liner 1, is built up in sections and there is provided at the top of the tunnel, in the concrete A, a number of channels 8, 9, 10, 11, 12, 13 and 14 identical with the channels 3, 4 and 5 at the bottom. The channels 3 to 5 and 8 to 14 accommodate an enclosure or light metal form 15 between which, and the concrete, is disposed a resilient element B, such for instance, as asbestos paper surrounding the membrane 1 and initially held in place by adhesive or the drainage ropes 6.

Within each of the channels and welded to the plate 16, constituting the membrane liner 1 for the tunnel, is a longitudinally split tubular element 17, the edges of the split 18 being welded as at 19 and 20 on each side to the adjacent edges of plates 21 and 22 forming a portion of the liner or membrane 1.

The space between the split tubular element 17 and the light metal casing 15 is filled with loose material, such as shot or sand, so that when the total metal membrane 1 is fabricated by welding, or the like, so that it lies closely adjacent the concrete, with the exception of such spacing as is afforded it by, for instance, the protrusion, if any, of the ropes, and the asbestos paper, the whole metal membrane 1 is resilient and may breathe or expand and contract to a certain extent so as to distribute its load evenly throughout the concrete encasing the same, and yet should any water accumulate between the metal membrane and the concrete, the pressure will be relieved by the checkered network of ropes forming wicking providing passages eventually directing drainage to the conduit drain tube 2.

With reference to Figure 3, plates 21 and 22 and the element 17 welded thereto as at 19 and 20, are identical with the structure described in connection with Figure 2, but the box like structure designated in Figure 2 as 15 and forming the enclosure for the sand or shot surrounding the split tubular member 17, and in this instance indicated as 23, is formed of Z shaped members 24 and 25 welded as at 26 and 27 respectively, to the outside of the plates 21 and 22 in a longitudinal direction with respect to the axis of the tunnel, penstock or conduit. Overlying the top of these Z shaped members to close the space between the same, and welded thereto as at 28 and 29, is a cover plate 30. As in the case of the construction shown in Figure 2, the outside of this channel 23, as well as the entire outside of the membrane, is overlaid with asbestos paper 31 and the ropes 32 in the same manner as is described previously. One important difference from the construction shown in Figure 2 is the sealing strip 33 which overlaps the slot 18, and is welded longitudinally only to the plate 21 as at 34, the said strip 33 having a slip joint fit with the plate 22.

In connection with the construction shown in Figure 4 the plates 21 and 22, which have been similarly designated throughout the description of Figures 2 and 3, have longitudinally riveted thereto the channel members 35 and 36 secured to the plates 21 and 22 by rows of rivets designated at 37 and 38 and which rivets also serve to secure in place the flanges 39 and 40 of the inverted U shaped channel member 41 covering the split 42 between the plates 21 and 22 and which on the inside, or pressure side, of the tun-

nel, penstock or conduit, is covered by the slip plate 43 welded as at 44 to the plate 21 and having a slip joint with the plate 22. The top or open side of the channel thus formed by the members 35 and 36 is closed by a cover plate 44' secured in place by screws 45 on each side and threaded into the flanges of the members 35 and 36 respectively; here, again, this channel thus formed is overlaid with asbestos paper, or the like, 46, and the ropes 47 as was the case in the construction shown in both Figures 2 and 3.

With reference to Figures 8 to 10 inclusive, the construction is not radically different from that just described in connection with the preceding figures except as relates to the channel members permitting expansion and contraction, and replacement of the ropes with other means. In this case the same plates 21 and 22 referred to in connection with the preceding figures and having the split between closed by the tubular element 47 as in Figure 1, are enclosed by the L shape members 48 and 49 forming a channel covered by the cover plate 50, all of which are welded or otherwise secured together, and have inside thereof reticulated material 51 such as fine wire mesh which will retain the shot or sand within the channel; the cover plate 50 as well as the L shape side members 48 and 49 being provided with holes, as shown, and indicated at 52 for drainage purposes. In this instance the ropes of the preceding structures described are replaced with a flexible metallic conduit 53, welded or otherwise secured in place; the box or channel like member, as in the previous instance, being overlaid with asbestos or similar paper 54, and in the bottom channel of this construction and leading to the drain 2 are nipples 55, all of the channels being connected to one another, as shown by this flexible metallic tubing which not only takes the water from the channels themselves but permits the infiltration of water along its length.

In building up this type of construction, the tunnel is first formed in the earth and concrete blocks or other spacing means are provided at the bottom to receive the bottom 30° portion of the cylindrical steel membrane with its longitudinal expansion joints, and the concrete is then placed beneath this portion of the membrane. The side portions of the membrane are then built up in sections and supported while concrete is placed behind the same, leaving the top one-third still to be finished, and when these plates are put in place with their respective longitudinally arranged expansion joints, the remaining concrete between the membrane and the tunnel wall can be put in position by the gun type or other method.

In this way there is built up a metal membrane lined tunnel which may expand and contract as pressure is applied and taken off, and which seals the concrete work and yet is provided with safety means preventing the building up of pressure between the metal lining and the concrete of the tunnel.

In certain materials it will be found necessary to install the supporting lining progressively as the tunnel heading is advanced, especially through "ravelly ground" or in certain forms of shale which, while quite firm and dense so long as they are protected from the air, disintegrate very rapidly as soon as air contacts them. When conditions of this nature obtain, the concrete, usually placed after the fluid tight membrane sections have been assembled in their final posi-

tion in the tunnel, is poured prior to the installation of the membrane and the longitudinal recesses to receive the expansion joints of the fluid tight membrane are formed in the concrete, thereby making it unnecessary to provide the metal boxes previously described for encasing these. The membrane units are then installed with their asbestos wrappings pasted to their exteriors and are placed directly against the preformed surface of the concrete lining which has checkerboard grooves formed in it to carry drainage to the bottom conduit, thus eliminating the impregnated lashing ropes previously described.

The space between the longitudinal recesses formed in the concrete and the exterior surfaces of the expansion joint members of the fluid tight membrane is filled with sand, shot, or other material which accommodates the slight movements which occur here and which will, at the same time, adequately support these parts against the internal fluid pressure which they must withstand.

In applying the fluid tight membrane to the preformed concrete lining as just described, it is essential that it closely contact the supporting enclosing surfaces thereof, and to accomplish this the forms employed to install the concrete are stripped of their drainage groove forming ridges and the members which form the longitudinal expansion joint recesses, and are re-erected in radial units with the corresponding units of the fluid tight membrane clamped to their exterior surfaces; and after a complete cylindrical section is in place these forms are then expanded by suitable jacking means until the sections of the fluid tight membrane are brought into firm contact with enveloping surfaces of the previously formed concrete, whereupon the membrane sections are joined by welding, or other suitable means as previously described, after which the forms are then collapsed and withdrawn and the process again repeated.

While in the foregoing there has been described specific constructions and methods in connection with the present invention, it will be observed that these may be modified in accordance with existing conditions on the job in hand without departing from the scope of the invention as expressed in the appended claims defining the same; for instance, in connection with the Pierre shales and other similar geological structure, change in temperature is accompanied by the destructive effect upon the shales and thus might require special treatment where joining the plates either longitudinally or along the channels, and it might be impossible to use direct welding as has been described in connection with the foregoing specific instance.

I claim:

1. A pressure tube within an earthen passage inclusive of a pressure resistant concrete lining for the same, and a resilient metal membrane co-extensive with and lying closely adjacent to the inside surface of said lining.

2. A pressure tube within an earthen passage inclusive of a pressure resistant concrete lining for the same, a resilient metal membrane co-extensive with and lying closely adjacent to the inside surface of said lining, and means between the lining and membrane relieving fluid pressure.

3. A pressure tube within an earthen passage inclusive of a pressure resistant concrete lining for the same, a resilient metal membrane co-extensive with and lying closely adjacent to the

inside surface of said lining, and a drainage net-work between the lining and membrane to relieve fluid pressure.

4. A pressure tube within an earthen passage 5 inclusive of a pressure resistant concrete lining for the same, a resilient metal membrane co-extensive with and lying closely adjacent to the inside surface of said lining, said membrane having longitudinally split junctures lengthwise 10 of the concrete lining, and means between the lining and membrane relieving fluid pressure.

5. A pressure tube within an earthen passage 15 inclusive of a pressure resistant concrete lining for the same, a resilient metal membrane co-extensive with and lying closely adjacent to the inside surface of said lining and longitudinally split, longitudinally split resilient means closing the aforementioned splits, yielding means between the concrete and said resilient means, and 20 a drainage net-work of ropes impregnated with water soluble material and lying between the metal and the concrete to relieve pressure.

6. A pressure tube within an earthen passage 25 inclusive of a pressure resistant concrete lining for the same, a resilient metal membrane co-extensive with and lying closely adjacent to the inside surface of said lining and longitudinally split, longitudinally split resilient means closing the aforementioned splits, a drainage net-work 30 of ropes impregnated with a water soluble substance and disposed between the metal and the concrete to relieve pressure, and a slippage element between the ropes and the metal to reduce the friction between the passage wall and metal 35 membrane.

7. A pressure tube within an earthen passage, 40 the natural walls of which are of a character to withstand the pressure load imposed by the fluid in the tube, inclusive of a resilient sealing membrane of metal co-extensive with and lying 45 closely adjacent the wall of the passage, means interposed between the passage wall and the membrane substantially eliminating irregularities of the passage wall, and drainage means between the passage wall and said membrane.

8. A pressure tube within an earthen passage, 50 the natural walls of which are of a character to withstand the pressure load imposed by the fluid in the tube, inclusive of a resilient sealing membrane of metal co-extensive with and lying 55 closely adjacent the wall of the passage, means interposed between the passage wall and the membrane substantially eliminating irregularities of the passage wall, and means between the passage wall and membrane affording slippage between the two.

9. The method of building a pressure tube of 60 concrete with a metal membrane liner of resilient construction with drainage and slippage means between comprising the steps of excavating an earthen passage, assembling metal mem-

brane liner sections within the passage while spacing the same from the wall thereof and interposing the drainage and seepage means, and then placing concrete intermediate the passage wall and membrane to eliminate irregularities and fix the location of the drainage and slippage means. 5

10. A pressure tube within an earthen passage, a pressure resistant concrete lining for the same, a resilient metal membrane co-extensive with 10 and lying closely adjacent to the inside surface of said lining and longitudinally split, longitudinally split resilient means closing the aforementioned splits, yielding means between the concrete and said resilient means, and a drainage 15 net-work between the metal and the concrete to relieve pressure.

11. The method of building a pressure tube of concrete with a metal membrane liner of resilient construction with drainage means between 20 comprising the steps of excavating an earthen passage, erecting within the passage a metal liner of resilient construction and coextensive longitudinally and transversely with the earthen passage while interposing drainage means between the same, and then placing concrete 25 between the liner and passage walls to eliminate irregularities.

12. As an article of manufacture, a tubular metal membrane for pressure tunnel lining and 30 having longitudinal splits closed by similarly split resilient tubes welded thereto.

13. As an article of manufacture, a tubular metal membrane for pressure tunnel lining and 35 having longitudinal splits closed by similarly split resilient tubes welded thereto, and a slip joint split closing lip for each split.

14. As an article of manufacture, a tubular metal membrane for pressure tunnel lining and having longitudinal splits closed by similarly 40 split resilient tubes welded thereto, a slip joint split closing lip for each split, and means enclosing a yieldable material surrounding the said resilient tubes.

15. A tubular structure for carrying fluid 45 under pressure within an earthen passage which comprises a tubular concrete wall coextensive with the passage wall, and a closely adjacent impervious yieldable membrane coextensive with and independent of the concrete and restrained 50 by the concrete against internal pressure deformation beyond the limit of its yieldability.

16. A tubular structure for fluids under pressure which comprises a tubular concrete wall, a closely adjacent impervious yieldable membrane 55 coextensive with and independent of the concrete and restrained by the concrete against internal pressure deformation beyond the limit of its yieldability, and means between the concrete and membrane assisting relative movement. 60

PHILLIP A. KINZIE.
